REFRIGERATING APPARATUS

Richard H. Swart, Royal Oak, Mich.

Application March 20, 1944, Serial No. 527,267

4 Claims. (CL. 62—8)

This invention relates generally to refrigerating apparatus and refers more particularly to an improved device for controlling the flow of the refrigerating medium or liquid refrigerant from the receiver of the condenser to the evaporator or cooling unit of the apparatus.

One of the essential objects of the invention is to provide a device of the type mentioned that may be utilized in place of and has advantages over an expansion valve or a float structure or a capillary tube for controlling the flow of the refrigerating medium to the evaporator. For example, the commonly used thermostatic expansion valve is more expensive to manufacture, has more moving parts and is apt to have leaks at the bellows or diaphragms thereof. The ordinary float structures take up more space, involve more parts and likewise are more expensive to manufacture. The capillary tubes have very limited application because it is impossible for them to feed the liquid refrigerant correctly except at one specific suction pressure for a specific discharge pressure, or specific room temperature. During the conditions of excessive room temperatures, the discharge pressure of the refrigerant will be above a given or predetermined amount, hence such tubes will feed a mixture of liquid, vapor or flash gas to the evaporator, with the result that there is an important decrease in refrigeration efficiency and cooling capacity of the evaporator just at a time when it is needed most. At lower room temperatures than the specific conditions permitting correct feed, such tubes pass insufficient refrigerant for efficient operation. Float valves, and expansion valves which are also commonly used for feeding refrigerants, require a multiplicity of accurately fabricated parts which are expensive, and subject to wear and frequently need repair or replacement. Thus, the conventional devices mentioned are unsatisfactory or expensive to install and repair.

Another object is to provide a device having elements formed of materials provided with different thermal coefficients of expansion disposed in heat exchange relation to the return or suction conduit for the refrigerating medium flowing from the evaporator to the compressor so that slight variations in the temperature of the suction conduit will cause relative movement between the elements of the device.

Another object is to provide a device wherein one of the elements just mentioned is preferably in the form of a tube or conduit for the refrigerating medium flowing from the receiver of the

condenser to the evaporator and serves as a valve seat for a valve carried by the other of said elements, so that the action of the valve to control the flow of refrigerating medium to the evaporator is responsive to relative movement between such elements.

Another object is to provide a device which will "unload" the compressor at the start of a cooling cycle, by permitting the suction pressure and discharge pressure to equalize.

Another object is to provide a heat exchange between the warm liquid refrigerant entering the device and the cold suction vapor returning from the evaporator in order to secure high thermodynamic efficiency from the refrigeration system.

Another object is to provide a device for limiting the suction pressure of the compressor to a value below which the motor is not overloaded.

Another object is to provide a device that is simple in construction, economical to manufacture, easy to install and efficient in operation.

Other objects, advantages and novel details of construction of this invention will be made more apparent as this description proceeds, especially when considered in connection with the accompanying drawing, wherein:

Figure 1 is a diagrammatic view of refrigerating apparatus having a device embodying my invention;

Figure 2 is an enlarged fragmentary vertical sectional view through the return conduit and the device embodying my invention;

Figure 3 is a sectional view taken substantially on the line 3—3 of Figure 2;

Figure 4 is a sectional view taken substantially on the line 4—4 of Figure 2;

Figure 5 is a view similar to Figure 3 but showing a slight modification.

Referring to the drawing, A is a device embodying my invention forming a section or part of the supply conduit B for the refrigerating medium flowing from the receiver C of the condenser D to the evaporator or cooling unit E of a refrigerating apparatus. F is the return or suction conduit for the refrigerating medium flowing from the evaporator E to the compressor H, and J is a conduit for the refrigerating medium flowing from the compressor H to the condenser D.

As shown, the device A is in heat exchange relation to the return conduit F and preferably comprises a tube 10 of stainless steel or other suitable material of low thermal expansion, a rod or wire 11 of copper or other suitable material of high thermal expansion, and a valve 12 on

the rod 11 and engageable with the adjacent end 13 of the tube 10 to control the flow of refrigerating medium from the tube 10 to the evaporator E.

Preferably the tube 10 telescopically engages and is terminally connected to adjacent sections of the conduit B, while the rod 11 within said tube is fixed or anchored at its forward end to the tube 10 but otherwise is free with respect thereto. At its free rear end the rod 11 is threaded to permit adjustment thereon of the valve 12 so that such valve may be adjusted properly relative to its seat 13 at the adjacent end of the tube.

The forward end 14 of the rod may be flattened and soldered to a bell shaped portion 15 of the tube 10, as illustrated in Figure 3, or may be fixed to a spider-like sleeve 16 rigid with the tube 10, as illustrated in Figure 5. In fact, any suitable rigid connection between the forward end of the rod 11 and the tube 10 may be employed, as desired.

In use, the tube 10 of the device is soldered or otherwise secured in thermal contact with the return conduit F throughout substantial portions of their length, as illustrated in Figure 1 so that such tube 10 will be in thermal contact with said conduit. Thus, the tube 10 serves as a heat transfer element between the return conduit F and the liquid flowing through conduit 10, thence to rod 11. The rod 11 will therefore change in length with respect to conduit 10 as influenced by changes in temperature of the return vapor in conduit F. In a refrigeration system it is necessary to control the "superheat" of the suction vapor in the evaporator outlet conduit to obtain efficient performance of the system. If the temperature of the vapor is at or slightly above the evaporating temperature of the refrigerant, the presence of unevaporated liquid is indicated. If the temperature of the vapor is abnormally high, the evaporator surface is inadequately utilized. Therefore, my device permits control of the superheat temperature in the return conduit F. For example, when the refrigerant vapor temperature entering the conduit F is highly superheated, the conduit 10 and the liquid therein and rod 11 are not cooled, then the rod 11 will lengthen with respect to the tube 10, and the opening between the valve 12 and end of the tube 13 will be relatively great. This permits a greater rate of liquid refrigerant flow to the evaporator, resulting in the vapor superheat in conduit F decreasing. In case the vapor becomes cooler than the desired superheat, the conduit F receives additional heat from the incoming liquid refrigerant, lowering the temperature of the liquid, the conduit 10 and the rod 11. As the conduit 10 and rod 11 cool, the rod 11 shortens with respect to tube 10, causing the valve 12 to move closer to seat 13, thereby restricting the rate of liquid flow. Thus, a substantially balanced condition is provided, inasmuch as the superheat of the refrigerant vapor in conduit F serves to regulate the valve opening between 12 and 13.

What I claim as my invention is:

1. In a refrigerating apparatus of the compressor-condenser-evaporator type, the combination with a return conduit for conducting refrigerating medium from the evaporator to the compressor, of a double restrictor structure in an evaporator feed conduit for controlling the flow of refrigerating medium from the condenser to the evaporator and comprising a single length of

open ended tubing having a cross section less than that of said feed conduit and extending throughout the major portion of its length lengthwise of and in thermal contact throughout substantially its entire length with the exterior of said return conduit, said tubing of less cross section forming a part of said feed conduit for conducting refrigerating medium from the condenser to the evaporator, and means for modifying the output of said tubing of less cross section including a valve at the outlet end of said tubing, and an actuating rod for said valve fixed to said tubing at the inlet end thereof, said rod and tubing being formed of materials having different thermal coefficients of expansion so that a differential in expansion and contraction of said elements is obtained under varying temperature conditions of said return conduit.

2. In a refrigerating apparatus of the compressor-condenser-evaporator type, the combination with a return conduit for conducting refrigerating medium from the evaporator to the compressor, of a feed conduit for conducting refrigerating medium from the condenser to the evaporator and including as a part thereof a double restrictor structure for controlling the flow of refrigerating medium to said evaporator, said double restrictor structure comprising a single length of open ended tubing having an outwardly flared inlet end and provided from said flared inlet end to its outlet end with a restricted passage for the refrigerating medium, said tubing extending throughout the major portion of its length lengthwise of and in thermal contact throughout substantially its entire length with the exterior of said return conduit, and means for modifying the output of said tubing, including a valve at the outlet end of said tubing, and an actuating rod for said valve extending therewith through the restricted passage aforesaid of said tubing and fixed to the flared inlet of said tubing, said rod and tubing being formed of materials having different thermal coefficients of expansion so that a differential in expansion and contraction of said elements is obtained under varying temperature conditions of said return conduit.

3. In a refrigerating apparatus of the compressor-condenser-evaporator type, the combination with a return conduit for conducting refrigerating medium from the evaporator to the compressor, of a feed conduit for conducting refrigerating medium from the condenser to the evaporator and including as a part thereof a double restrictor structure for controlling the flow of refrigerating medium to said evaporator, said double restrictor structure comprising a single length of open ended tubing provided throughout substantially its entire length with a restricted passage for the refrigerating medium, said tubing extending throughout the major portion of its length lengthwise of and in thermal contact throughout substantially its entire length with the exterior of said return conduit, and means for modifying the output of said tubing, including a valve at the outlet end of said tubing, and an actuating rod for said valve extending therewith through the restricted passage aforesaid of said tubing and fixed to the said tubing at the inlet end thereof, said rod and tubing being formed of materials having different thermal coefficients of expansion so that a differential in expansion and contraction of said elements is obtained under varying temperature conditions of said return conduit.

4. In a refrigerating apparatus of the compressor-condenser-evaporator type, the combination with a return conduit for conducting refrigerating medium from the evaporator to the compressor, of a feed conduit for conducting refrigerating medium from the condenser to the evaporator and including as a part thereof a double restrictor structure for controlling the flow of refrigerating medium to said evaporator, said double restrictor structure comprising a single length of open ended tubing extending throughout the major portion of its length lengthwise of and in thermal contact throughout substantially its entire length with the exterior of said return conduit, and means for modifying the output of 15

5 said open ended tubing, including a valve at the outlet end of said tubing, and an actuating rod for said valve attached thereto at the outlet end of said tubing, said rod extending through 10 and cooperating with the interior of said tubing to form therein a passage of less cross section than said feed conduit, said rod being fixed to said tubing at the inlet end thereof, said rod and tubing being formed of materials having different thermal coefficients of expansion so that a differential in expansion and contraction of said elements is obtained under varying temperature conditions of said return conduit.
